CATHODE-RAY TUBE

Milton R. Schulte, Basking Ridge, N. J., assignor
to Tung-Sol Lamp Works, Inc., Newark, N. J.,
a corporation of Delaware

Application November 3, 1949, Serial No. 125,271

4 Claims. (Cl. 313—71)

1

This invention relates to cathode ray picture tubes used in television.

There is at present in the commercial field the return cathode ray tube credit policy of guaranteeing twelve or eighteen months of service to customers some of whom may in this time actually use the tube for a comparatively small number of hours while others such, for instance, as tavern keepers, are likely to use the tube many times longer in the same interval.

This credit policy presents a serious problem to the cathode ray tube manufacturer and the television set manufacturer since neither of them at present has any accurate method of determining whether a cathode ray tube has actually been operated the intended guaranteed actual service period.

By my present invention I have solved this problem by devising a cathode ray tube which indicates accurately and fairly for the cathode ray tube manufacturer, the television set manufacturer and the set owner whether the cathode ray tube at any particular time has operated the intended guaranteed hours of actual operation.

A further object of the invention is a cathode ray tube of the above indicated character which can be produced by the manufacturer at a cost of only a few cents more at most than the present cost of cathode ray tubes.

Further objects of the invention will herein-after appear.

For a better understanding of the invention reference may be had to the accompanying drawings forming a part of this application, wherein

Fig. 1 illustrates schematically a conventional cathode ray picture tube embodying the invention;

Fig. 2 is a perspective view of the exhaust end of the cathode ray tube shown in Fig. 1 with certain parts broken away;

Fig. 3 is a similar perspective view of a modification;

Fig. 4 is a similar perspective view of another modification; and

Fig. 5 is a similar perspective view of another modification.

Referring to Fig. 1 of the drawings I have illustrated my invention as embodied in a conventional cathode ray tube having a gun part 1, a picture screen part 2 and a flaring casing part 3 between the inner end of the gun part 1 and the screen part 2.

In the particular embodiment of Fig. 1 the exhaust tube for the cathode ray tube is indicated at 4 and in that embodiment I have illustrated my invention as being located at least in part

in this exhaust tube. The indicating part of the invention is designated by the numeral 5 and this is devised to indicate accurately within small tolerances when the cathode ray tube has had a normal number of life expectancy hours of burning or operation as, for example, the intended guaranteed hours, under the present credit policy mentioned above.

In this embodiment of the invention the indicator 5 is an electrically heated filament operating either in the high vacuum of the cathode ray tube or in a high vacuum in its own miniature container. It is designed and pre-life tested to burn out at the expiration of the normal number of life expectancy hours of the actual energization of the cathode ray tube. This electrically heated filament 5 in practice may be designed so as accurately to indicate this period of actual use or energization of the cathode ray tube within plus or minus ten (10%) percent.

The filament 5 must be incorporated in the cathode ray tube in a manner to be energized wherever the cathode ray tube is connected in circuit by energization preparatory to operation and during operation. For this purpose the filament is provided with electrical conductors 6 and 7 which in the particular embodiment shown directly carry the filament 5 at one end and are mechanically held in spaced relation by an insulating bead 8 of any suitable character. The filament 5 may thus be energized through the electrical conductors 6 and 7 by its own electrical energy source as, for example, a battery, omitted for convenience in illustration, with the cathode ray tube being provided with suitable leading in connections to energize the filament 5.

With a view to minimizing expense in cathode ray tube manufacture I prefer however to energize the electrically heated filament 5 from conventional terminals already provided in the cathode ray tube as, for example, the terminals 10 and 11 leading in from the transformer or other supply source for the tube filament. This connection with this source has the additional advantage that the filament 5 is energized by the same source and at the same voltage that the cathode heating filament is energized, the electrical conductors of the latter being designated in Fig. 2 by the numerals 12 and 13. The energization of the filament 5 is therefore assured at each energization of the cathode ray tube and is always in circuit during the energization of the tube and by reason of its special design and construction and operation in a high vacuum it will burn out at or approximately at the normal number of guaranteed life expectancy hours of the cathode ray tube. This can be depended upon

therefore accurately to indicate fairly for the benefit of the tube manufacturer, the set manufacturer, and the set owner whether the cathode ray tube has actually operated the normal or guaranteed number of life expectancy hours of burning. The expensive and onerous return cathode ray tube policy in vogue at the present time may therefore be entirely dispensed with.

In the embodiment of Figs. 1 and 2 I have illustrated only one indicating filament but it is understood that instead of one filament 5 there may be multiple filaments connected in parallel across the energized leads 6 and 7. For instance, in Fig. 3 I have illustrated multiple filaments connected across the lead wires 6 and 7 and in this particular embodiment I have illustrated two such filaments 15 and 16. These filaments 15 and 16 may be if desired designed and pre-life tested either to burn out after the same number of hours of energization or after different hours of energization. If the former the two filaments will guard against a rarely occasional bad filament indicator or short life indicator indicating a false life history to the cathode ray tube since both filaments must fail in order to indicate the full normal number of life expectancy hours of the cathode ray tube. In this embodiment of Fig. 3 the filaments 15 and 16 are also disposed within the exhaust tube 4 and are operated in the high vacuum of the cathode ray tube.

In the embodiment of Fig. 4 I have illustrated the life expectancy indicating filament 20 as embodied in its own miniature housing or container 21, the latter being supported in any suitable manner at the exhaust end of the cathode ray tube. The housing or container 21 may be of any shape desired and in the particular embodiment shown it assumes the shape of a miniature tipless lamp bulb. The housing or container 21 may be exhausted to the high vacuum required for accurate indication of the filament 20 or if desired it may be open at one end so as to permit the operation of the filament 20 at the high vacuum of the cathode ray tube.

In the embodiment of Fig. 5 the life expectancy indicating filament 5 is suitably mounted in a capsule or short tube 25 having either or both ends open to the high vacuum of the cathode ray tube. This capsule or tube 25 may be mounted in any suitable manner, the particular mounting forming no part of the present invention.

Thus by this invention the necessity for the expensive and onerous credit return tube policy may be dispensed with or its complications and uncertainties obviated. For instance, on the return of a cathode ray tube to a set manufacturer or tube manufacturer by the set owner, it may be accurately and quickly determined whether the cathode ray tube has in fact operated the normal number of life expectancy hours as, for instance, by visual or other suitable testing of the indicating filament or filaments in the cathode ray tube for remaining life thereof. Further, the indicator is visible to the set owner and he can be instructed not to claim credit on tubes with unlighted indicators, thus saving him the expense of returning a tube on which he will not receive credit.

The burning out of the indicator filaments does not prevent the functioning of the cathode ray tube for any hours of the remaining life the tube may be capable of producing. The glowing of the indicator filament, the latter being disposed at the exhaust end of the tube will not interfere with the production of the picture on the tube screen since the filament is of miniature capac-

ity and also since it is disposed so far away from the screen with the gun mechanism disposed therebetween. If desired a metal or mica shield may be interposed between the indicator and the body of the tube to reduce the light passing to the main body of the tube. I have indicated schematically in Figs. 2 and 3 such a shield 30. In the embodiment of Figs. 4 and 5 the containers 21 and 25 may be darkened so as not to give out any ambient light. This invention has the added advantage that the abuse of high line voltages which reflect on the life of the cathode ray tube would also reflect on the life of the life indicating filaments. But the processing voltages required on the tube during manufacture would not affect the indicator life because it could be connected parallel to the tube filament in the base of the tube even tho it had been sealed into the tube itself.

I claim:

1. The combination with a cathode ray tube having a cathode heating filament and support leads therefor, of a second filament having a predetermined life disposed within the cathode ray tube and connected across and supported by the support leads for the heating filament, said second filament serving to indicate when the tube has operated a predetermined number of hours.

2. The combination according to claim 1 wherein said second filament is disposed in the exhaust end of the tube and the glow therefrom when energized is visible without destruction of the tube.

3. The combination with a cathode ray tube having a cathode heating filament and a sealed off exhaust tube at one end thereof, of means for indicating when the tube has operated a predetermined number of hours, said means comprising a filament having a predetermined life disposed within the exhaust tube and electrically connected in parallel with the cathode heating filament.

4. The combination with a cathode ray tube having terminals for application of operating voltages to the electrodes thereof, of a filament of predetermined number of hours of life disposed within the tube and means coupling said filament with certain of said terminals for energization of said filament whenever operating voltages are applied to the tube, said last mentioned means being operable to energize said filament irrespective of the proper functioning of the tube and to permit functioning of the tube independently of the condition of said filament whereby proper functioning of the tube after expiration of life of the filament is an indication that the tube has operated at least said predetermined number of hours and, conversely, energization of the filament when the tube fails to function is an indication that the tube has failed prior to said predetermined number of hours of operation.
